UNITED STATES PATENT OFFICE.

WILLIAM F. NORTH, OF PHILADELPHIA, PENNSYLVANIA, ASSIGNOR OF ONE-HALF TO SAMUEL P. COFFAN, OF SAME PLACE.

WATER-CLOSET.

SPECIFICATION forming part of Letters Patent No. 362,034, dated April 26, 1887.

Application filed June 19, 1886. Serial No. 205,683. (No model.)

To all whom it may concern:

Be it known that I, WILLIAM F. NORTH, a citizen of the United States, residing in the city and county of Philadelphia, State of Pennsylvania, have invented a new and useful Improvement in Water-Closets, which improvement is fully set forth in the following specification and accompanying drawings, in which—

10. Figure 1 represents a vertical section of a water-closet embodying my invention. Fig. 2 represents a vertical section of a portion thereof at a right angle to Fig. 1. Fig. 3 represents a bottom view of a detached portion on an enlarged scale. Fig. 4 represents a vertical section in line x x , Fig. 3.

Similar letters of reference indicate corresponding parts in the several figures.

My invention consists of improvements in 20 water-closets, as will be hereinafter fully set forth.

Referring to the drawings, A represents a water-closet bowl, having at top a rim, B, forming a passage, C, for water. At the bottom of the bowl is a valve-chamber, D, which is connected with said bowl and the soil-pipe E, and communicates therewith.

F represents a downwardly-opening valve, which is located within the chamber D and 30 pivoted to the wall thereof. Fitted to the valve are laterally-moving locking-pieces G, which, when the valve is closed, enter recesses H in the sides of the chamber D, whereby the valve is firmly supported and tightly closed 35 and locked. The pieces G are recessed near their inner ends, as at a, leaving blocks J with inclined faces, with which faces engage inclined projections K on a slide, L, which is located between the upper and lower plates of 40 the valve.

M represents a lever, which is mounted on the bearing pin or axis N of the valve, and having at its pivotal portion a cam, P, which bears against the slide L, so as to move the latter when the valve is to be lowered, the 45 effect of which is the unlocking of the pieces G from the walls of the recesses H. One limb of the lever M bears against the under side of the valve, and the other limb is pivoted to a link, M', to which latter is pivoted a handled rod, Q, by which the valve is operated.

A weighted arm, R, is connected with the rod Q and with a chain, R', which passes around a pulley, R², and is connected with a lever, S, on the tank or cistern S' of the flushing device, 55 said pulley being supported on the box which incloses the bowl A.

The valve-seat has a grooved gasket, T, and the upper side of the valve has a rib, U, which, when the valve is closed, is compressed into 60 the gasket, forming a tight joint, whereby water cannot escape from the bowl, and sewer-gas is prevented from returning to the bowl.

When the rod Q is raised, the cam P, rotating with the lever M, moves the slide L, so 55 that the pieces G are withdrawn, and as the valve is no longer held by said pieces it drops, and is accordingly open, whereby the contents of the bowl are discharged. When the rod is let go, the lever M, actuated by the weighted 70 arm R, quickly raises the valve, and the slide L, no longer controlled by the cam P, is returned to its first position by the action of the springs T', each of which bears against the block J of one of the pieces G and the head of 75 the other piece G, so that both pieces are forced outwardly and directed into the recesses H, whereby the valve is again held in locked position.

Connected with the tank or cistern S' is an 80 outlet-pipe, A', which leads to the bowl A, and also connected with said tank is a supplemental tank, S², which has an outlet-pipe, A², the latter being in communication with the pipe A'. Rising from the pipe A' is a valve-seat, A³, and rising from the tank S² is a valve-seat, A⁴, said seats being turned inwardly at top, so as to form close joints with the valves W W', which are formed of rubber or other soft material and secured to the head X, which, 85 by means of a rod, X', is connected with the lever S. Depending from the head at the side carrying the valve W is a rod, Y, to whose lower end is secured a valve, Z, whose seat Z' is at the bottom of the tank S² or top of the 90 pipe A².

When the lever S is raised, the valves W W' are opened and the valve Z is closed. Water now flows through the pipe A' and washes the bowl, and the tank S² is also filled, the water 100 in the bowl passing through the open valve F to the sewer or cesspool. When the valve F

closes, the lever S returns to its normal position, whereby the valves W W' close and the valve Z opens, whereby the water in the tank S² flows through the pipe A² and enters the bowl, remaining thereon as a seal.

Buffers F', of elastic or flexible material, are secured to the valve-chamber D in such position that when the valve drops it strikes said buffers, the latter acting as stops and preventing noise, which would otherwise be occasioned should the valve directly strike the wall of the chamber.

Should the springs T' fail to hold the pieces G in the recesses H, the weight R³ of the arm R, forcing down the link M', causes the upper limb of the lever M to bear firmly against the valve, whereby the latter is unfailingly held closed on its seat.

The upper end of the link M', which receives the lower end of the rod Q, is recessed, the walls of which abut against the rod and limit the lateral play of said link, so that it does not strike the walls of the chamber within which it is located.

Having thus described my invention, what

I claim as new, and desire to secure by Letters Patent, is—

1. In a water-closet, the hinged valve F, with axis N, in combination with lever M, mounted on the axis N and provided with an upper arm adapted to support said valve F, a link and rod connected to a lower arm of said lever M, fastening devices for said valve, substantially as described, and a cam for operating said fastening devices, all substantially as described.

2. The chamber D, with recesses H, the locking-pieces G, with blocks J, slide L, with projections K, and springs T', combined and operating substantially as and for the purpose set forth.

3. The valve having sliding pieces G and a slide, K, which engages with said pieces, in combination with a cam which operates said slide, substantially as and for the purpose set forth.

WM. F. NORTH.
